CLAIM

The ornamental design for a soap bar, as shown and
described.

DESCRIPTION

FIG. 1 is a top plan view of a soap bar showing my new
design, the bottom view being identical;

FIG. 2 is a front elevational view thereof, the rear elevational
view being identical;

FIG. 3 is a cross sectional view taken along the plane 3—3
in FIG. 1;

FIG. 4 is a right side view thereof, the left and right sides
being identical; and,

FIG. 5 is a perspective view thereof.
